AUTOMATIC SHAKEOUT DEVICE FOR TIGHT
FLASK MOLDSAlfred C. Christensen, Chicago, Ill., assignor, by
mesne assignments, to Herbert Simpson Cor-
poration, Chicago, Ill., a corporation of Illinois

Application August 31, 1948, Serial No. 47,020

1 Claim. (Cl. 22—1)

This invention relates to foundry equipment. More particularly, this invention has to do with an improved device for automatically removing the sand and the solidified casting from a tight flask mold and further contemplates the delivery of the sand and the casting to a screen member for separation of the loose sand from the casting and the subsequent delivery of each to a separate conveyor for removal from the molding area.

Heretofore, the above-mentioned operations have been performed manually in disconnected operations with resulting expenditure of much man power. In a large foundry the automatic carrying out of these steps will be of a great asset to the molding procedure.

It is, therefore, an important object of the present invention to provide means for automatically removing the sand and the solidified casting from a tight flask mold.

Another object of the present invention is to provide means for automatically removing the sand and solidified casting, separating the sand from the casting, and delivering these to separate conveyors.

According to the teaching of the present invention there is provided a substantially horizontal conveyor on which the assembled mold including the bottom board, the cope, the drag and the sand mold and the casting therein are carried along. As the mold travels along on the conveyor, the arm or handle extending outwardly from either side of the drag passes over a pair of chains, one on either side of the conveyor, which are traveling in the same direction as the conveyor but are moving upwardly at an angle thereto. The chains lift the cope and drag and contents off the bottom board which remains on the conveyor. When the flask and its contents are elevated, approximately two feet, they pass through a shakeout station where one of the spokes of a revolving wheel enters the flask and pushes the sand and casting downwardly out of the flask into a chute which is disposed in the space between the bottom board on the conveyor and the shakeout station. The chute directs the sand and the casting to an inclined screening member where the sand is screened off into a hopper leading to a conveyor while the casting moves along to the end of the inclined surface where it drops onto another conveyor. The cope and drag are then carried by the chains and returned to the first conveyor and the bottom boards thereon.

Other and further objects, features and advantages of the present invention will be appar-

ent to one skilled in the art from the following detailed description taken in connection with the accompanying drawings.

On the drawings:

- 5 Figure 1 is a plan view of the novel shakeout device of the present invention shown incorporated in a foundry production line;
- 10 Figure 2 is a vertical sectional view taken substantially on line II—II of Figure 1;
- 15 Figure 3 is a vertical sectional view taken on line III—III of Figure 1;
- 20 Figure 4 is an enlarged vertical sectional view of a portion of Figure 3;
- 25 Figure 5 is an enlarged fragmentary vertical sectional view taken on line V—V of Figure 2;
- 30 Figure 6 is an enlarged fragmentary elevational view, with parts in section, of a second embodiment of the shakeout device of the present invention; and
- 35 Figure 7 is an enlarged elevational view, with parts in section, of a third embodiment of the shakeout device of the present invention.

As shown on the drawings:

- 40 It is believed that my novel process of ejecting sand and casting from a flask type mold will be best understood from a description of apparatus adapted to practice the same.

In Figures 1, 2 and 3 the reference numeral 10 is a conveyor, the conveying surface of which travels in a substantially horizontal plane. This conveyor may be of any standard type such as the conveyor illustrated in Figures 1 and 4 wherein a plurality of elongated trays 12, having overlapping end portions, are pivotally mounted on carriages 13, each of which has a downwardly extending yoke portion 14 carrying an axle 15 on which a wheel 16 is rotatably journaled. The wheel is arranged to move along a track 17 secured to a supporting base 18. Rollers 19 are associated with each carriage 13 for guided movement between angle members 20 secured to the upper portion of the base 18. This type of conveyor, which is described in detail in the patent issued to A. C. Christensen et al., U. S. Patent No. 2,168,898, permits molds to be conveyed in a circuitous route through various processing stages in the foundry.

In Figure 2 a straight portion of the mold conveyor 10 is illustrated. On either side of this conveyor and substantially parallel thereto an endless chain 23 is mounted. Each of these chains is engaged, as shown at the extreme left end of Figure 2, by a sprocket 24 which is secured to a shaft 25 journaled in bearings 26 mounted on rigid support blocks 27. At the ex-

treme right end of Figure 2 each chain is engaged around a sprocket 29 which is keyed or otherwise secured to an axle 30 journaled in bearing 31 on a support platform 32 of a frame structure 33. The shaft 30 is driven by a pair of gears 35 secured thereto at the side of the conveyor (Figure 2) and are in mesh with gears 36 mounted thereabove on a shaft 40 journaled in bearings 41 which are secured to an upper platform 42 of the frame structure 33. An electric motor 43 (Figure 1) drives the shaft through a speed reducer 44 and a coupling 45.

As viewed in Figure 2, the upper portion of each chain 23 is arranged to be pulled to the right by the associated sprocket 29. Rollers 48 (Figure 4) disposed over the pins which connect the links on either side of the chain ride on a track provided by an upright plate 50 which extends for substantially the entire length of the chain conveyor. A plate 50 is provided for each chain and may be suitably supported by cross braces 52 secured between spaced channel members 53 (Figure 2) which are supported by legs 54 to define a guide structure 55 having one slanted portion 55a leading up to the shakeout station, a second slanted portion 55b leading downwardly therefrom, and a central substantially horizontal section 55c therebetween. Thus, as seen in Figure 2, the chains 23 are guided and supported as they pass under the side arm 56 of the drag and lift the flask with its contents off the bottom board, which remains on the mold conveyor 10. The chains 23 then carry the flask and its contents to the shakeout station at the horizontal portion 55c of the guide structure 55, where the contents of the flask are removed as will hereinafter more clearly appear as this specification proceeds. The chains 23 then carry the flask downwardly to the plane of the mold conveyor 10 returning it to said mold conveyor and the bottom boards thereon in a continuous operation.

In their reverse travel, the chains 23 are slack and are supported on a plurality of rollers 57 mounted from a frame member 58 of the guide structure.

This distance between the central substantially horizontal portion 55c of the guide structure 55 which defines the shakeout station and the flat mold conveyor therebelow is preferably about two feet, although more or less clearance may be used.

A chute 59 (Figures 1, 2 and 3) underlies the opening between the channel members 53 at the shakeout station and has a lower portion 59a slanted laterally of the conveyor to direct the sand and casting pushed out of the flask into a screening member 60. This member may advantageously be of the inclined rotary type wherein a large cylinder or drum 61, having a perforated surface, is provided with exterior gear rings 63 which are in mesh with drive gears 64 secured on shaft 65 driven by a motor 66. With this type of screening member the sand will be worked out through the perforated surface as it slides toward the lower end and will be deposited in a hopper 68 leading to a conveyor 70 while the casting will be deposited over the end onto a conveyor 72 which will take it to a predetermined point in the foundry. A dust hood 71 may be disposed over the screening member 61 to direct the dust to a suitable collector.

It is evident, of course, that instead of the rotary type of screening member 61 any other suitable type may be used, such as a vibrating screen type.

A preferred embodiment of the device of this invention which is effective to push the contents out of the flask as it moves along the chain conveyor comprises a wheel 73 (Figure 2) keyed to an axle 74 which is journaled in bearing members 75 disposed on the upper surface of the outer free ends of spaced pivoting arm members 76 herein illustrated as an I-beam. At the pivoting end of the arm members 76 a plate 77 (Figures 1 and 2) is rigidly secured across the arm members 76, causing them to pivot as a unit. Bearing blocks 79 secured in an aligned upright position on the upper surface of the plate 77 are arranged to receive a shaft 78 which is further journaled in spaced bearing blocks 81 disposed on the upper surface of a box-like frame structure 84 which straddles the conveyor mechanism and provides a support structure for the push-out wheel.

As best seen in Figure 4, an adjustment device 86 is disposed between the under side of one of the arms 76 and a bracket 87 extending outwardly from a vertical member 84a of the frame structure 84. This device is effective to pivot the arms 76 as a unit about the shaft 78 to adjust the depth of penetration of the arms of the wheel into the flask. This adjusting device may conveniently comprise a flat-headed bolt 89 welded on the arm 76 and a nut 90 which is threaded onto the bolt and is resting on the brackets 87 which has a hole through which the bolt may extend.

Thus, the wheel 73 is mounted for rotation on a shaft 74 which is journaled at the outer free end of a pair of arms mounted for pivoting, adjustable movement.

The wheel 73 is rotated by means of a chain 92 which is in engagement with a sprocket 93 keyed to the shaft 78 and a sprocket 94 keyed to the shaft 74. The shaft 78 is driven by an electric motor 95 through a speed reducer 96 and a coupling 97.

As illustrated in Figures 2 and 5, a swinging hammer 100 is pivotally mounted on a rod 101 which is secured between upright members 102 and 103 which may be suitably secured as by welding to arms 104 extending upwardly from the channel members 53. It will be noted that this swinging hammer is disposed at the shakeout station at a point in advance of the point where the spoke of the wheel pushes the contents out of the flask. Thus, when the empty flask approaches the hammer 100 it will lift it up, and as the flask passes therewith the hammer 100 will be tripped to strike a blow on the inner side of the flask substantially in the center thereof and shake out any loose sand which might be still clinging to the side of the flask.

It is obvious, of course, that the successful operation of the wheel 73 will depend upon the synchronization of the movement of the wheel with the movement of the chain conveyor and the molds thereon. The manner in which the arms of the wheel enter the mold and leave the mold is clearly illustrated in Figure 2. In the present invention it is proposed to use an electrical means for synchronizing the drive of these two units. A suitable control of this type is known as the "synchrolock" wherein various motors throughout the plant can be driven at a predetermined synchronized speed. Thus, in the present invention this electrical control may be connected to the motor 95 which drives the sprockets for rotating the wheel 73 and the electric motor 43 which drives the sprockets of the chain conveyor, and thus the operation of the

wheel may be coordinated with the molds on the chain conveyor. Then when the mold assemblies are placed on predetermined positions on the conveyor, the wheel will automatically be timed with the movement of the mold assemblies.

In Figure 6 is shown a second embodiment of the novel shakeout device of the present invention. This embodiment comprises a pneumatic or hydraulic cylinder 106 supplied with a fluid under pressure through an opening 107 and pivotally mounted on a frame structure 108 for actuating a lever arm 109 which is also pivoted on the structure 108 for moving the outer end of the lever 109 into the mold as the mold is aligned thereunder. The operation of this pneumatic hammer could be automatically timed with the positioning of the mold therebeneath by means of a switch actuated by the flask or the handle 56 extending outwardly from the flask as it approaches the shakeout position. The switch can be arranged to actuate other mechanism to energize the pneumatic cylinder for actuating the lever arm 109.

In Figure 7 a third embodiment of the shakeout device of the present invention is illustrated. This embodiment comprises an induction-type magnet 112 supported on a structure 113. The magnet when energized will raise the flask approximately two inches and the impact against the magnet will liberate the sand and casting from the flask. The energization of the magnet, of course, may be automatically timed with the chain conveyor by mechanism actuated by the flask itself as it reaches the shakeout position.

A still further embodiment of the shakeout mechanism of the present invention would involve the positioning of a man with a hammer at the shakeout station to strike a blow to the center of the flask to dislodge the contents as the mold assembly is positioned over the shakeout station.

It will, of course, be understood that various details of construction may be varied through a

wide range without departing from the principles of this invention, and it is, therefore, not the purpose to limit the patent granted thereon otherwise than necessitated by the scope of the appended claim.

I claim as my invention:

In a conveyor system for tight flask molds including bottom boards having flasks resting thereon with handles projecting laterally from the sides thereof, a mold conveyor movable in a generally horizontal plane and supporting said tight flask molds on the bottom boards thereof with said handles projecting laterally therefrom, an endless chain extending along each side of said conveyor, and driven to travel in the direction of said conveyor, means guiding said chains in parallel upwardly inclined paths from the plane of said mold conveyor from points spaced along said conveyor from the receiving end thereof to an intermediate shakeout station and then downwardly to the plane of said mold conveyor in advance of the discharge end thereof, said chains engaging the handles of said flasks as said flasks move with said mold conveyor and lifting said flasks above the bottom boards on said mold conveyor to said shakeout station and then returning the empty flasks to said mold conveyor and the bottom boards thereon in a continuous operation.

ALFRED C. CHRISTENSEN.
